POLISHING MACHINE

Herbert S. Indge, Westboro, Mass., assignor to
 Norton Company, Worcester, Mass., a corporation of Massachusetts

Application December 10, 1937, Serial No. 179,157

20 Claims. (Cl. 51—59)

The invention relates to abrading machines, and more particularly to a polishing machine for polishing spaced cylindrical portions on a work piece.

5 One object of the invention is to provide a thoroughly practical polishing machine for polishing spaced cylindrical portions on a work piece, such as for example a completely assembled motor armature shaft. It is another object 10 of this invention to provide a polishing machine in which the work piece, such as an armature shaft or the like, is supported to rotate an abrasive on an abrasive work support, such as a rigidly supported flexible abrasive element or a bonded abrasive element which serves simultaneously to support and polish the spaced portions on the work piece. A further object of 15 the invention is to provide such a machine with a frictional driving wheel which is arranged frictionally to engage and rotate the work piece during the polishing operation.

A further object of the invention is to provide a polishing machine for polishing spaced cylindrical portions on a work piece while it is supported on an abrasive work supporting member in which the abrasive is formed as a roll of continuous flexible abrasive material which is arranged so that it may be automatically advanced after each polishing operation so as to present a 20 fresh abrading surface for the next work piece to be polished. A further object of the invention is to provide an abrasive work support in which two spaced parallel normally non-rotatable bonded abrasive elements serve to support 25 and polish a work piece and are automatically indexed to present a fresh abrasive surface before or after each polishing operation. Other objects 30 will be in part obvious or in part pointed out hereinafter.

40 The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

45 Fig. 1 is a front elevation of the improved shaft polishing machine, having parts of the base broken away and shown in section more clearly to show the driving mechanism;

50 Fig. 2 is a right end elevation of the machine, having parts broken away and shown in section

more clearly to show the driving and operating mechanism;

Fig. 3 is a plan view of the machine; Fig. 4 is a fragmentary longitudinal sectional view, taken approximately on the line 4—4 of Fig. 3, showing the mechanism for reciprocating the abrasive supporting carriages;

Fig. 5 is a fragmentary cross sectional view, on an enlarged scale, taken approximately on the line 5—5 of Fig. 4, showing the carriage reciprocating mechanism and the drive therefor;

Fig. 6 is a fragmentary perspective view, on an enlarged scale, showing the mechanism for automatically actuating the driving clutch;

Fig. 7 is a fragmentary detail elevation of the driving clutch actuating mechanism, taken approximately on the line 7—7 of Fig. 1;

Fig. 8 is a fragmentary end elevation, on an enlarged scale, of a modified form of abrasive work support; and

20

Fig. 9 is a fragmentary end elevation, on an enlarged scale, of a modified form of abrasive work support.

One embodiment of the improved polishing machine for polishing cylindrical work pieces has 25 been disclosed in the drawings comprising a base 10 which supports a plurality of longitudinally reciprocable slides or tables 11, 12, 13 and 14. In order that the slides 11, 12, 13 and 14 may be reciprocated or oscillated rapidly, an anti-friction bearing support therefor is provided. The base 10 is provided with spaced parallel longitudinally extending V-ways 15 and 16 each of which supports a row of balls 17 and 18, respectively. The tables 11, 12, 13 and 14 are each 30 provided with a V-way 19 resting on the balls 17 and a flat way 20 resting on the balls 18 so that the tables 11, 12, 13 and 14 may be readily oscillated or reciprocated at a rapid rate.

This machine is particularly intended for the 40 polishing of spaced cylindrical work pieces on a cylindrical piece of work. For example, in the manufacture of electric motors, it is desirable to put a final polish on the bearing surfaces of the motor shaft after the armature has been completely assembled and the armature is ready for installation in the motor. To facilitate polishing such work pieces at a rapid rate, the improved machine is arranged as a duplex machine, so that while one shaft is being polished, another 45 polished shaft may be removed and a new shaft loaded in place, thereby increasing the output of the machine. To accomplish this result, the pair of tables 11 and 12 are utilized to support an armature shaft 21 and the tables 13 and 14 50 55

are arranged rotatably to support an armature shaft 22.

Each of the slides or tables 11, 12, 13 and 14 are provided with work supporting brackets 23, 24, 25 and 26, respectively. These brackets are spaced longitudinally from each other and arranged in pairs simultaneously to support spaced portions of a work piece, such as an armature shaft. In the preferred form, each of the work supporting brackets 23, 24, 25 and 26 is provided with a pair of spaced parallel rollers 27 and 28 (Fig. 2) which are rotatably supported by a pair of studs 29 and 30, respectively. The studs 29 and 30 are carried by the bracket 26. The rollers 27 and 28 on the brackets 25 and 26 are arranged to support end portions 35 and 36 of an armature shaft 37 for a polishing operation. Similarly, the corresponding rollers 27 and 28 on the work supporting brackets 23 and 24, respectively, serve to support and polish spaced portions 38 and 39 of an armature shaft 40.

The work supporting rollers 27 and 28 serve as a support for a flexible abrasive element so that when the armature shaft is rotated relative thereto, a polishing operation will be produced on the desired portions of the armature shaft. A continuous strip of flexible abrasive material, such as abrasive paper or cloth 45, is provided in the form of a roll 46 rotatably supported on a shaft 47 carried by the base 10. The abrasive paper 45 passes over the upper surfaces of the work supporting rollers 28 and 27 and passes under the same and over a rotatable idler roller 49 and reels up on a spindle 50 which is supported in suitable bearings in the base 10. From this disclosure it will be readily apparent that when a work piece is placed upon the abrasive paper 45, the weight of the armature shaft or work piece to be polished will cause the paper to wrap around a portion of the work piece and allow it to drop into the position as illustrated in Fig. 2. In this position of the work piece, the work piece is rotated.

Similarly, a roll 46a of flexible abrasive paper 45a is rotatably mounted on the inner end of the shaft 47 and is arranged to pass over a work supporting element carried by the work supporting member 25. The abrasive strip 45a passes over the rollers 28 and 27 carried by the work supporting member 25 and is wound up on the spindle 50. When a work piece, such as an armature shaft 22, is placed in position with the spaced bearing portions 35 and 36 resting on abrasive paper 45a and 45, respectively, the abrasive paper will be depressed to wrap around the surface of the portions 35 and 36, so that when the armature shaft 22 is rotated, the rotation of the shaft on the abrasive paper surface will be polished to the desired extent.

A similar abrasive paper assembly is provided for the work supporting members 23 and 24. A rotatable shaft 52 is rotatably journaled in suitable bearings in the base 10 and serves as a support for rolls 53 and 53a of abrasive paper 54 and 54a which pass over the work supporting surfaces on work supporting members 23 and 24 so as to provide abrasive supports for spaced portions 38 and 39 on the armature shaft 21.

In the manufacture of electric motors and other similar pieces of apparatus having rotatable elements which rotate at a rapid rate, it is frequently desirable to assemble the rotor on its shaft and to put a final polish on the bearing surfaces of the shaft after the assembly of the 75 rotor is completed. In such an operation, it is

desirable to provide a driving mechanism whereby the rotor and its shaft may be rotated during the polishing operation without the necessity of a clamping dog to drive the same. In the preferred form, a friction work driving wheel 55 is arranged to be moved into frictional contact with the periphery of the armature 37 of the shaft 22 to rotate the same and thereby produce a polishing action upon the bearing portion on the armature shaft. The friction driving wheel 55 may be of any suitable material, such as a bonded abrasive wheel, abrasive covered or coated wheel, a leather covered wheel, or a rubber wheel, which when brought into contact with the periphery of the armature 37 will rotate and drive the same. The friction wheel 55 is carried by a spindle 56 which is journaled in suitable bearings 57 and 58 which are formed integral with or fixedly mounted on a pivotally mounted arm 59 which is arranged to swing about the axis of 10 the shaft 60 as a pivot so that it may be moved toward and from an operating position to start and stop the rotation of the work piece as desired.

The wheel spindle 56 carries at its outer end 25 a multiple V-groove pulley 61 which is connected by V-belts 62 with a multiple V-groove pulley 68 on a shaft 67. The shaft 60 is supported in brackets 41 and 42 which project upwardly from the rear portion of the base 10. A driving motor 63 is mounted on the rear of the base 10. The motor 63 is provided with an armature shaft 64 which carries a multiple V-groove pulley 65. A pair of V-belts 66 engage the center pair of grooves of the pulley 65 and pass around a multiple V-grooved stepped pulley 66 which is fixedly mounted on the rotatable shaft 67. The shaft 67 carries a multiple V-grooved pulley 68 which is connected by V-belts 62 with the pulley 61 on the end of the wheel spindle 56 so as to transmit a rotary motion from the motor 63 to the frictional work driving wheel 55 to produce a rotation of the work during the polishing operation. The belts 66 may be shifted to other steps on the stepped V-groove pulley to change the speed of the work driving wheel when desired. The motor 63 is preferably mounted so that it may be adjusted in a vertical direction to tension the driving belts 66 as desired and to facilitate changing of driving wheel speeds when desired. The motor 63 is also pivotally mounted so that it may be adjusted about a stud 70 to tension a driving belt 71 to be hereinafter described.

A similar work driving unit is provided for rotating the armature shaft or work piece 21 supported on the work supporting members 23 and 24. A work driving wheel 75 is supported on a spindle 76 which is journaled in bearings 77 and 78 which are carried by a pivotally mounted arm 79 which is pivoted to swing about the shaft 60 as a pivot to swing the driving wheel 75 toward or from the armature 40 of the armature shaft 21. The spindle 76 is provided with a multiple V-pulley 81 which is connected by a pair of V-belts 82 with a pulley 83 mounted on the shaft 60.

It is desirable to provide a stopping and starting mechanism for controlling the rotation of the work driving wheels 55 and 75. The V-groove pulleys 68 and 83 are preferably rotatably mounted on the shaft 67. In order to transmit the rotary power of the motor 63 to the driving wheels 56 and 75, respectively, a clutch 72 and 73 are interposed between the driven shaft 61 and the pulleys 68 and 83, respectively. The clutches 72 and 73 have not been illustrated in detail, since 75

they are not considered to be a part of the present invention, but merely a conventional showing of a cone and clutch has been illustrated. When the clutch member 72 is moved toward the left (Fig. 3), it is thrown into engagement so that the rotary power of the shaft 67 is transmitted to rotate the pulley 68 which in turn, through the V-belt 62 rotates the work driving wheel 55. Similarly, when the clutch member 10 73 is moved toward the right (Fig. 3), it is thrown into engagement to lock the pulley 83 to the shaft 67 so that the rotary motion of the shaft 67 is transmitted through the pulley 83 and belt 82 to rotate the work driving wheel 75. A yoke 15 74 is mounted on the end of a rotatable shaft 90 and is arranged to actuate the clutch 72 when desired. Similarly, a yoked member 91 is mounted on the end of a rotatable shaft 92 and is arranged to actuate the clutch 73 to stop and start 20 the rotation of the work driving wheel 75.

The abrasive paper becomes worn and the abrasive particles dulled after a polishing operation. To insure a uniform polishing action on successive pieces of work, it is desirable to provide 25 an automatic indexing mechanism which serves automatically to index the paper to present a fresh abrading surface for each polishing operation. The spindle 50 on which the abrasive paper 45 is arranged is provided with a ratchet 30 wheel 85. A bell crank lever 86 is pivotally supported on the spindle 50 and is provided with a pawl 87 engaging the teeth on the ratchet wheel 85. The upper end of the vertically slidably rod 88 is arranged in the path of the pivotally mounted arm 59 and its lower end is arranged to engage the bell crank lever 86 so as to actuate the pawl 87. When the arm 59 is swung downwardly into an operating position (Fig. 2), the rod 88 moves downwardly, rocking the bell crank lever 86 in a 35 clockwise direction to cause an idle movement of the pawl 87 over the teeth of the ratchet wheel 85. After a polishing operation has been completed and the work driving wheel moved upwardly to an inoperative position, the released compression of a spring pressed plunger 89 serves 40 to rock the bell crank lever 86 in a counterclockwise direction and causes the pawl 87 to rotate the ratchet wheel 85 in a counterclockwise direction to wind up a small amount of the used abrasive paper 45, thereby presenting a fresh 45 abrading surface in position for the next polishing operation.

The pawl and ratchet mechanism above described serves not only automatically to index the strip of abrasive paper 45 but also serves to index the strip of abrasive paper 45a.

A similar automatic indexing mechanism comprising a pawl and ratchet mechanism (not shown) is provided for automatically advancing the abrasive paper 54 and 54a in timed relation with the movement of the work driving wheel 45 to and from an operating position before and after a polishing operation. It should be noted that the rotation of the work is such that any thrust on the abrasive paper 45 is taken up by the pawl 87 and ratchet wheel 85. The work driving wheel 55 rotates in a clockwise direction, as indicated by the arrow in Fig. 2. This transmits a rotary motion to the armature 37 to rotate it in a counterclockwise direction, thus producing a thrust on the abrasive paper tending to unwind it from the spindle 50.

To facilitate removal of a polished piece of work and insertion of a new piece of work, it is desirable to provide a suitable mechanism for

moving the work driving wheel to and from an operating position. In the preferred form, a fluid pressure mechanism is mechanically connected so that the swinging arms 59 and 79 may be readily and independently rocked to and from an operating position. As illustrated in the drawings, a toggle lever mechanism is provided comprising a toggle lever 94 which is pivotally connected by a stud 95 with the arm 59. A second toggle lever 96 is rotatably supported on a shaft 97 which is journaled in suitable bearings 98 on the base 10 of the machine. The adjacent ends of the toggle levers 94 and 96 are pivotally connected together by means of a stud 99. The toggle lever 96 is preferably formed as a bell crank lever having a downwardly projecting arm 100 which is connected by a stud 101 with the outer end of a piston rod 102. A piston 103 is fixedly mounted on the inner end of the piston rod 102 and is slidably mounted within a 20 fluid pressure cylinder 104. In order to prevent free movement of the bell crank lever, the cylinder 104 is preferably pivotally supported so that it may readily swing as the parts move. The cylinder 104 is pivotally connected by means of a stud 105 which is in turn supported by a bracket 106 which is formed integral with the base 10.

It is desirable to provide a suitable fluid pressure system including a control apparatus, whereby fluid under pressure may be readily admitted to either end of the cylinder 104. A fluid pressure system has been illustrated comprising a fluid reservoir 109 which is formed integral within the base 10. A fluid pump 110 pumps fluid from the reservoir 109, through a pipe 111, and forces fluid under pressure through a pipe 112 to a control valve 113. A pipe 114 connected with the pipe 112 is provided with a pressure relief valve 115 which is preferably of the adjustable type, so that a desired pressure may be maintained within the fluid pressure system. If the pressure within the system builds up over the desired pressure, the relief valve 115 opens, thus conveying excess fluid under pressure to the reservoir 109.

The control valve 113 is preferably a balanced piston type valve comprising a valve stem 116 having formed integrally therewith valve pistons 117, 118 and 119. In the position of the parts as shown in Fig. 2, fluid under pressure passing through the pipe 112 enters a valve chamber between the valve pistons 117 and 118 and passes outwardly through a pipe 120 and into a cylinder chamber 121 at the left end of the cylinder 104 to cause the piston 103 to move into the position illustrated in Fig. 2, thus rocking the toggle levers 95 and 97 so as to swing the arm 59 and the work driving wheel 55 into operative frictional engagement with the periphery of the armature 37 to rotate the armature and its supporting shaft 21 and to cause a relative rotation between the flexible abrasive element and the spaced bearing portions on the shaft to be polished. During the movement of the piston 103 toward the right (Fig. 2) to swing the work driving wheel 55 into operative contact with the armature, fluid within a cylinder chamber 122 is exhausted therefrom through a pipe 123 into a valve chamber between the valve pistons 118 and 119 and out through a pipe 124 into the reservoir 109.

The valve 113 is preferably manually controlled by means of a manually operable lever 125 which is pivotally mounted on a stud 126 supported in a bracket 127 secured to the base 10. The control lever 125 is operatively connected with the 75

valve stem 116. The lever 125 is provided with an enlarged portion 128 (Fig. 1) which has an elongated aperture therein which straddles a spool-shaped member 129 mounted on the outer end of the valve stem 126. The lever 125 is provided with a pair of inwardly projecting pins 130 which ride within the groove of the spool shaped member 129 so that when the control lever 125 is rocked about its supporting stud 126 it is a pivot, the valve stem will be shifted to control the direction of flow of fluid to and from the cylinder 104.

After the bearing portions 35 and 36 on the armature shaft 22 have been polished to the desired extent, the control lever 125 is rocked in a clockwise direction to cause the valve stem 116 to move toward the left (Fig. 2), thus shifting the valve pistons 117, 118 and 119 so as to reverse the flow of fluid to and from the cylinder 104. In the new position of the valve, fluid under pressure from the pipe 112 enters a valve chamber formed between the valve pistons 118 and 119 and passes through the pipe 123 into the cylinder chamber 122 to cause the piston 103 to move toward the left (Fig. 2). This movement causes the bell crank arms 100 and 96 to rock in a clockwise direction, thus rocking the toggle lever 94 in a counterclockwise direction until the toggle levers 94 and 96 approach a straight line position, thus rocking the arm 59 in a clockwise direction to swing the work driving wheel 55 to an inoperative position to facilitate removal of the polished piece of work and the insertion of a new piece thereinstead.

During the movement of the piston 103 toward the left (Fig. 2) fluid within the chamber 121 is exhausted through pipe 120, into the valve chamber between the valve pistons 117 and 118, and out through the pipe 124, into the reservoir 109.

A similar fluid pressure piston and cylinder actuated toggle lever mechanism is provided to swing the arm 79 to move the work driving wheel 75 to and from an operating position. Each of these mechanisms is independently controlled so that while one of the mechanisms is in an operative position, the other may be in an inoperative or loading position. A toggle lever 135 is pivotally mounted by a stud 136 to the arm 79. A bell crank lever having an upwardly extending arm 137 is pivotally mounted on the shaft 97 and is connected by a stud 138 with the lower end of the toggle lever 135. The bell crank 137 is provided with a downwardly extending arm 140 which is connected by a stud 141 with a piston rod 142 which is connected with a piston (not shown) within a cylinder 143. The cylinder 143 is pivotally supported in a manner similar to that shown for the cylinder 104. A manually operable control lever 145 is pivotally supported by a stud 146 to a bracket 147 supported on the base 10. The lower end of the lever 145 is provided with an enlarged portion 148 which is connected to move a valve stem 149 of a control valve (not shown). The control valve together with the cylinder 143 is identical with that previously described and it is, therefore, believed it is not necessary to illustrate this construction in detail. By manipulation of the control lever 145, the driving wheel 75 may be moved to and from an operating position independently of the movement of the driving wheel 55.

Reciprocating mechanism

In order to prevent rings being formed around the periphery of the work due to single abrasive

grains scoring the work during the polishing operation, it is desirable to provide a relative reciprocating movement between the abrasive element and the shaft to be polished so as to provide not only a rotary but a relative reciprocating movement between the abrasive element and the shaft being polished. This is preferably accomplished by reciprocating the abrasive supporting elements simultaneously in opposite directions, thereby counteracting any tendency to shift the work piece longitudinally relative to the work driving wheel. As illustrated in the drawings, a rotatable shaft 175 is journaled in suitable bearings 176, 177 and 178 in the base 10. The shaft 175 carries a pair of eccentrics 179 and 180. The eccentric 179 is connected by a link 181 with a stud 182 which is carried by a rock arm 183, the lower end of which is pivoted by a stud 184 to the base 10. The upper end of the rock arm 182 is provided with a stud 185 which carries a square shaped bushing 186. The square shaped bushing 186 is slidably supported in a vertical slot which is cut in a depending projection 187 on the under side of the table 14.

Similarly, the eccentric 180 is connected by a link 190 with a stud 191 carried by a rock arm 192, the lower end of which is pivoted by a stud 193 to the base 10. The upper end of the rock arm 192 is provided with a stud 194 which carries a square shaped block 195. The block 195 slides in a vertically extending slot in a depending projection 196 on the under side of the table 13. It is readily apparent from the foregoing disclosure that motion transmitted by the eccentrics 179 and 180 is transmitted through the connecting links 181 and 190, respectively, to rock the rock arms 183 and 192, respectively, and thereby to reciprocate the tables 14 and 13, respectively, simultaneously and in opposite directions. Due to the sliding connection between the square shaped bushings 186 and 196 within the downwardly extending projections 187 and 196 of the tables 14 and 13, respectively, a reciprocatory motion may be transmitted to said tables without the tendency of lifting the tables 45 from their supporting ways.

The tables or slides 11 and 12 are similarly provided with a reciprocating mechanism comprising a shaft 200 (Fig. 1) which carries a pair of eccentrics 201 and 202 which are connected by links 203 and 204, respectively, to rock arms 205 and 206, respectively. The rock arms 205 and 206 are pivotally connected by means of stud 207 and 208, respectively, on the base 10. The upper ends of the rock arms 205 and 206 are connected by means of slidably mounted square shaped bushings 209 and 210, respectively, with the tables 11 and 12, respectively. Rotation of the shaft 200 and eccentrics 201 and 202 serves simultaneously to transmit a reciprocatory movement to the tables 11 and 12 simultaneously to reciprocate them in the opposite direction, so that the reciprocatory movement of one neutralizes the movement of the other upon the work piece so that the work piece will be maintained against an endwise movement.

In order to drive the reciprocating mechanism, a V-belt 71 transmits power from the motor pulley 65 to a pulley 215 which is mounted on a bushing 216 which is in turn rotatably supported on a shaft 217. The shaft 217 is rotatably supported in anti-friction bearings 218 and a similar anti-friction bearing (not shown) contained within the projecting boss 219 of the base 10. The shaft 217 is provided with a pulley 220.

mounted on its outer end which is connected by means of a V-belt 221 with a V-groove pulley 222 which is mounted on the outer end of the shaft 175. In order to transmit power from the pulley 215 to the shaft 217, a friction disk clutch 223 is interposed therebetween. A yoked member 225 carried by a shaft 226 and arranged to move a spool-shaped member 227 serves to engage or disengage the clutch 223 to start or stop the rotation of the shaft 175 and thereby to control the starting and stopping of the reciprocatory movement of the tables 13 and 14.

To facilitate loading of work pieces and removal of work pieces to and from the machine, it is desirable that the reciprocation of the abrasive work supports be stopped when the work driving wheel is moved to an inoperative position. In the preferred form, it is desirable to start and stop the reciprocation automatically in timed relation with the movement of the work driving wheel to and from an operating position. A downwardly extending projection 230 of the lever 125 is connected by means of a stud 231 with a link 232 which is connected to an arm 233 formed integral with the yoked member 225. It will be apparent from this disclosure that when the lever 125 is rocked in a clockwise direction to shift the control valve 213 and thereby cause a movement of the work rotating wheel 55 to an inoperative position, the clutch 223 will be disengaged, thereby stopping the reciprocation of the tables 13 and 14.

The shaft 200 which simultaneously reciprocates the tables 11 and 12 in opposite directions is driven in a similar manner. A V-belt 250 transmits power from the motor pulley 65 to a V-pulley 251 mounted on a rotatable sleeve 252 which is in turn rotatably supported on a rotatable shaft 253. The shaft 253 is journaled in suitable anti-friction bearings 254 and 255. A friction disk clutch 256 is interposed between the pulley sleeve 252 and the shaft 253. The shaft 253 is provided at its outer end with a V-grooved pulley 257 which is connected by a V-belt 258 with a pulley 259 mounted on the shaft 200. A clutch shifting member 260 associated with the clutch 256 is operatively connected in a manner similar to that described in connection with the clutch 223 so that when the control lever 145 is moved to cause a movement of the work driving wheel 75, either toward or from an operating position, the clutch 256 will be actuated so as to start the simultaneous reciprocation of the tables 11 and 12 in opposite directions when the driving wheel 75 is moved into engagement with the armature 40 of the shaft 21, or is disengaged when the work driving wheel 75 is moved out of engagement with the armature 40 after the polishing operation has been completed to stop the reciprocatory movement of the tables 11 and 12.

Automatic start and stop work rotation

In order to facilitate loading of the machine, it is desirable to provide an automatic mechanism whereby movement of the arms 59 and 79 toward or from an operating position serves to actuate the clutches 72 and 73, respectively, to start or stop the rotation of the work driving wheels 55 and 75, respectively. A lever 265 is fixedly mounted on the inner end of the shaft 75 so that in effect the yoked member 74 and the arm 265 form a bell crank lever. A link 266 is connected to the outer end of the arm 265 by means of a stud 267. The upper end of the link 266 is provided with an elongated slot 268. A stud 269 fixedly mounted

on the arm 59 rides in the elongated slot 268 and serves when the work driving wheel 55 is moved upwardly to an inoperative position to rock the arm 265 and the yoke 74 so as to disengage the clutch 72 and thereby stop the rotation of the wheel 55 automatically when it is moved to an inoperative position.

Similarly, an arm 270 is fixedly mounted on the inner end of the shaft 92 so that in effect it forms a bell crank lever with the clutch shifting yoke 91. A link 271 is connected by a stud 272 with the lever 270. The upper end of the link 271 is provided with an elongated slot 273. A stud 274 fixedly mounted on the arm 79 rides within the elongated slot 73 and serves when the work driving wheel 75 is moved downwardly into an operating position to rock the lever 270 and thereby shift the yoke 76 to engage the clutch member 73 and start the rotation of the work driving wheel 75 as it approaches an operating position. The rotation of the wheel 75 is stopped when it is moved to an inoperative position out of contact with the work piece being polished.

A modified form of work supporting member has been illustrated in Fig. 8. For certain types and sizes of work, it may be desirable to provide a concave work supporting surface for supporting the abrasive strip instead of providing a pair of spaced rollers. As illustrated in Fig. 8, an abrasive supporting member 160 is provided with an upper concave partial cylindrical surface 161 over which extends a continuous strip of abrasive paper 163. The curvature of the surface 161 preferably is the same as or of a greater radius than that of the finished work piece. The abrasive paper 163 passes over an idler roller 164 and an idler roller 165 and may be wound up by means of a pawl and ratchet mechanism, as above described in connection with the disclosure in Fig. 2.

In polishing certain types of work, it may be desirable to utilize a bonded abrasive wheel instead of a flexible abrasive element, as shown in Figs. 1 to 7 inclusive. As shown in the modification illustrated in Fig. 9, an abrasive supporting member 235 serves as a support for a pair of bonded abrasive wheels 236 and 237. These wheels are arranged with their axes parallel to each other on studs or spindles 238 and 239 and are spaced apart by a sufficient distance so that they form spaced abrasive supports for a work piece 240. A work driving wheel 241 is rotatably supported on a pivotally mounted support 242 and is arranged to be moved into frictional engagement with the work piece 240 to rotate the same relative to the abrasive wheels 236 and 237 for a polishing operation. During the polishing operation, the abrasive wheels 236 and 237 and the support 235 therefor are reciprocated longitudinally or axially in a manner similar to that shown in Figs. 1 to 7 inclusive.

In order to provide a fresh abrading surface for each polishing operation, a suitable mechanism is provided for normally holding the abrasive wheels 236 and 237 against rotation. This mechanism is preferably in the form of an indexing mechanism which is actuated automatically to index the abrasive wheels 236 and 237 a slight amount each time the work driving wheel 241 is moved toward and from an operating position. This mechanism comprises a gear train 70 including a gear 243 which is mounted to rotate the wheel 236, an intermediate gear 244 which is rotatably supported on the supporting member 235, and a gear 245 which is arranged to rotate the wheel 237. A ratchet wheel 246 is

mounted to rotate with the gear 245 and wheel 231. A pawl 247 is pivotally mounted on one arm of a bell crank lever 248, which lever is pivotally supported on the spindle 239. When the driving wheel is moved to an operating position, the pivotally mounted arm 242 which supports the driving wheel 241 moves a rod 249 downwardly to rock the bell crank lever 248 in a clockwise direction, causing the index pawl 247 to ride idly over the ratchet wheel 246. After the polishing operation has been completed and the work driving wheel 241 is moved upwardly to an inoperative position, the released compression of a spring pressed plunger 250 serves to rock the bell crank lever 248 in a counterclockwise direction, thereby causing the pawl 247 to rotate the ratchet wheel 246 and thereby index the wheel 231 a slight amount to present a new abrasive surface for the next work piece. At the same time, the rotary indexing movement is transmitted from the wheel 231 through the gears 245, 244 and 243 to rotate the abrasive wheel 236 a similar amount to present a new abrasive surface for the next polishing operation. It will be readily apparent that the pawl and ratchet mechanism may be so arranged and adjusted that the wheels may be indexed by small amounts merely sufficient to present a fresh abrading contact with the work piece on successive polishing operations.

The operation of this improved polishing machine will be readily apparent from the foregoing disclosure. An armature shaft 22 is placed in position with the bearing portions 35 and 36 resting on the strips of abrasive paper 45a and 45, respectively, thus depressing the paper and causing it to wrap around a portion of the bearing surface. The control lever 125 is then rocked in a clockwise direction to shift the control valve 113 so as to cause the work driving wheel 55 to rock into the position illustrated in Fig. 2. Movement of the work driving wheel 55 into an operating position automatically shifts the clutch 72 to start the rotation of the wheel 55. The shifting of the control lever 125 to start the approaching movement of the wheel 55 to an operating position also serves through the link 232 to actuate the clutch 223 to produce a simultaneous reciprocation of the tables 13 and 14 in opposite directions so as to cause a relative reciprocation between the work piece and the abrasive paper during rotation of the work piece on said paper.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. In a polishing machine, a continuous strip of flexible abrasive material, a supporting member having a partial cylindrical work supporting surface thereon to support said abrasive so as to form an abrasive support for a work piece to be polished, a rotatable work driving wheel which is arranged frictionally to engage and rotate a work piece, means to rotate said driving wheel, a pivotal support for the driving wheel,

toggle levers to swing said support, and means including a fluid pressure piston and cylinder which are operatively connected to actuate said toggle levers so as to swing said support and driving wheel to and from an operating position. 5

2. In a polishing machine, a continuous strip of abrasive material, a work supporting member having a concave surface thereon to support said abrasive element so as to form an abrasive support for a work piece to be polished, a rotatable work driving wheel which is arranged frictionally to engage and rotate a work piece, a pivotally mounted arm to support said wheel, and means including a fluid pressure operated piston and cylinder which are operatively connected to swing said arm. 10

3. In a polishing machine, a continuous flexible abrasive element, a pair of spaced parallel rollers to support said abrasive so as to form an abrasive support for a work piece to be polished, a rotatable work driving wheel which is arranged frictionally to engage and rotate a work piece, and means including a toggle lever mechanism to move said friction wheel toward and from said work piece. 20

4. In a polishing machine, a longitudinally reciprocable slide, a pair of spaced parallel rollers on said slide, a strip of flexible abrasive material on said rollers which is arranged to support a work piece for a polishing operation, a rotatable driving wheel which is arranged frictionally to engage and rotate a work piece supported thereon, means to move said friction wheel toward and from said work piece, and means relatively to reciprocate said rollers and 35 abrasive strip during a polishing operation.

5. In a polishing machine, a pair of longitudinally reciprocable slides, a pair of spaced work supporting members on each of said slides, a flexible abrasive element passing over each of 40 said supporting members which are arranged to form an abrasive support for spaced cylindrical portions on a work piece during a polishing operation, means including a rotatable driving wheel which is arranged frictionally to engage and rotate a work piece supported thereon, and means simultaneously to reciprocate said slides in opposite directions to cause a relative longitudinal movement between the abrasive element and work. 45

6. In a polishing machine, a longitudinally reciprocable slide, a work supporting member on said slide, a continuous flexible abrasive element which passes over said supporting member and serves to polish a work piece supported thereon, a rotatable driving wheel for a work piece, means including a clutch to rotate said wheel, means to move said frictional driving wheel into or away from operative contact with the work, and means actuated thereby to operate said clutch to start the rotation of the friction wheel when it is moved into an operating position. 55

7. In a polishing machine, a longitudinally reciprocable slide, a work supporting member thereon, a continuous flexible abrasive element passing over said supporting member and serving as a support to polish a work piece supported thereon, a friction driving wheel arranged to engage the periphery of a work piece to rotate the same, 70 means including a clutch to rotate said wheel, means including a fluid pressure operated piston and cylinder to move said friction wheel toward and from an operating position, and means actuated thereby to operate said clutch so as to 75

start the rotation of the wheel when it is moved toward an operating position.

8. In a polishing machine, a longitudinally reciprocable slide, a work support thereon, a flexible abrasive element passing over said work support and arranged to support and polish a work piece which is supported and rotated thereon, a rotatable work driving wheel which is arranged to engage and rotate a work piece, means to reciprocate said slide to cause a reciprocatory movement of the abrasive support for the work piece during rotation thereof, means including a fluid pressure operated piston and cylinder to move said wheel toward and from an operative position, a manually operable control valve to control the admission of fluid to said cylinder, and means including a clutch actuated by and in timed relation with movement of said valve to start the reciprocation of the slide when the wheel is moved toward an operating position.

9. In a polishing machine having a longitudinally reciprocable slide, a work supporting member, a flexible abrasive element passing over said member and arranged to support and polish a work piece which is supported and rotated thereon, means including a friction driving wheel which is arranged frictionally to engage and rotate a work piece, a pivotal support for said wheel, means including a clutch to rotate said wheel, means including a piston and cylinder to move said pivotal support to cause the wheel to move toward or from an operating position, a clutch actuating mechanism operated by movement of said pivotal support to engage said clutch when the wheel is moved toward an operating position, means to reciprocate said slide to produce a relative longitudinal movement between the abrasive element and said work piece, a manually operable control lever and a valve to control the admission of fluid to said cylinder, and a clutch which is actuated by said lever to start the reciprocation of said slide when the driving wheel is moved into an operating position.

10. In a polishing machine, a pair of spaced longitudinally reciprocable slides, a work supporting member on each of said slides, a continuous flexible abrasive element passing over each of said supports which are arranged simultaneously to support and polish spaced portions on a cylindrical work piece, a rotatable frictional driving wheel arranged to engage and rotate a work piece, means including a manually operable lever to move said frictional wheel to and from an operating position, means simultaneously to reciprocate said slides in the opposite direction, and means including a clutch actuated by said control lever to start reciprocation of said slides when the friction wheel is moved into an operating position.

11. In a polishing machine for polishing cylindrical work, a longitudinally reciprocable table, a pair of spaced rollers on said table, a rotatably mounted spool having a continuous strip of abrasive paper thereon, said abrasive paper passing over said spaced rollers, a spool located below said first spool and arranged to wind up used abrasive paper, a rotatable work driving wheel which is arranged frictionally to engage and rotate a work piece during a polishing operation, and means including a toggle lever mechanism to move said friction wheel toward and from said work piece.

12. In a polishing machine, a longitudinally reciprocable table, a pair of spaced rollers on said table, a roll of strip abrasive material the

strip of which is extended over said rollers, said spaced rollers and abrasive being arranged simultaneously to support and polish a cylindrical work piece, a rotatable roller upon which the used portion of the strip is wound, a rotatable work driving wheel which is arranged frictionally to engage and rotate the work piece during the grinding operation, and means actuated automatically by movement of said driving wheel to and from an operative position intermittently to 10 rotate said second roller automatically to advance the strip of abrasive material.

13. In a polishing machine, a longitudinally reciprocable slide, a rotatable work driving wheel which is arranged frictionally to engage and 15 rotate a work piece, means to reciprocate said slide, a work supporting member on said slide, a roll of strip abrasive material the strip of which extends over said work support to form 20 an abrasive support for the work piece to be polished, a rotatable roller upon which the used portion of said strip is wound, a pawl and ratchet mechanism to rotate said second roller, means actuated by movement of said driving wheel toward an operating position to move said pawl 25 idly over the ratchet wheel, and a spring pressed plunger which is rendered operative each time said driving wheel is moved to an inoperative position for drawing said abrasive strip over said work support a predetermined amount.

14. In a polishing machine, a pair of normally non-rotatable spaced abrasive wheels to form an abrasive support for a work piece to be polished, a rotatable work driving wheel which is 35 arranged frictionally to engage and rotate a work piece, a pivotal support for said driving wheel, means to rotate said driving wheel, and means to swing said support and driving wheel toward and from an operating position.

15. In a polishing machine, a pair of normally non-rotatable spaced abrasive wheels to form an abrasive support for a work piece to be polished, a rotatable work driving wheel which is arranged frictionally to engage and rotate a 45 work piece, means to rotate said driving wheel, means to move said driving wheel toward and from an operating position, and means to reciprocate said abrasive wheels longitudinally relative to said driving wheel while the driving wheel 50 is in an operative position.

16. In a polishing machine, a pair of normally non-rotatable spaced abrasive wheels to form an abrasive support for a work piece to be polished, a rotatable work driving wheel which is 55 arranged frictionally to engage and rotate a work piece, means to rotate said driving wheel, means to move said work driving wheel toward and from an operative position, and means including an indexing mechanism simultaneously to index said wheels to present a fresh abrasive surface when said driving wheel is moved to an inoperative position.

17. In a polishing machine, a pair of normally non-rotatable spaced abrasive wheels to form an 65 abrasive support for a work piece to be polished, a rotatable work driving wheel which is arranged frictionally to engage and rotate a work piece, means to rotate said driving wheel, means to move said work driving wheel toward and from 70 an operative position, means to reciprocate said abrasive wheels axially when the driving wheel is in an operating position, and means including an indexing mechanism automatically and simultaneously to index said abrasive wheels to pre- 75

sent a fresh abrasive surface for each successive polishing operation.

18. In a polishing machine, a pair of longitudinally reciprocable slides, an abrasive work support and polishing device on each of said slides simultaneously to support and polish spaced cylindrical portions on a work piece, a rotatable work driving wheel which is arranged frictionally to engage and rotate the work piece, and means simultaneously to reciprocate said slides in opposite directions so as to cause a relative longitudinal movement between the abrasive work support and the work piece.

19. In a polishing machine, a pair of longitudinally reciprocable slides, a work supporting member on each of said slides, a continuous flexible abrasive element passing over each of said supporting members simultaneously to support and polish spaced cylindrical portions on a work piece, a rotatable driving wheel which is arranged frictionally to engage and rotate a work piece,

and means simultaneously to reciprocate said slides in opposite directions so as to cause a relative longitudinal movement between the abrasive element and work.

20. In a polishing machine, a pair of longitudinally reciprocable slides, an abrasive work supporting and polishing member on each of said slides simultaneously to support and polish spaced cylindrical portions on a work piece, a rotatable work driving wheel which is arranged frictionally to engage and rotate a work piece, means to move said driving wheel into or away from engagement with the work piece, means simultaneously to reciprocate said slides in opposite directions to cause a relative longitudinal movement between the abrasive element and work, and means including an indexing mechanism simultaneously to index said abrasive work supporting and polishing members when the work driving wheel is moved to an inoperative position.

HERBERT S. INDGE.
